UNITED STATES PATENT OFFICE.

WILLIAM C. KAUFMAN, OF MORGANTOWN, WEST VIRGINIA.

AUTOMATIC STOP FOR TALKING MACHINES.

Application filed August 20, 1920. Serial No. 404,808.

To all whom it may concern:

Be it known that I, WILLIAM C. KAUFMAN, a citizen of the United States, residing at Morgantown, in the county 5 of Monongalia, and State of West Virginia, have invented new and useful Improvements in Automatic Stops for Talking Machines, of which the following is a specification.

10 This invention relates to talking machines, particularly to control devices therefor, and has for its object the provision of means associated with a talking machine of the Edison cylindrical type whereby upon 15 completion of the reproduction the mechanism will be automatically stopped.

An important object is the provision of a device of this character which is adjustable for cylinders of different lengths. 20 An additional object is the provision of a device of this character which will be simple and inexpensive in manufacture and installation, highly efficient in use, durable in service, and a general improvement in 25 the art.

With the above and other objects and advantages in view, the invention consists in the details of construction to be herein-after more fully described and claimed, 30 and illustrated in the accompanying drawings in which

Figure 1 is a plan view of a talking machine of the Edison cylindrical type showing my device in position thereon,

35 Figure 2 is a side elevation,

Figure 3 is a detail plan view of the brake beam,

Figure 4 is a detail cross sectional view showing the connection of the brake beam 40 with the cut-off lever of the machine,

Figure 5 is a cross sectional view showing the movable stop member mounted upon the brake member,

Figure 6 is a detail cross sectional view 45 through the adjustably mounted stop member showing the latch means thereon,

Figure 7 is an edge view thereof and

Figure 8 is a detail view of the yoke carrying bar.

50 Referring more particularly to the drawings, the letter A designates the top of a talking machine of the Edison type using a cylindrical record B which is rotated by means of gearing indicated at C and driven 55 by the usual motor construction which is not shown as forming no part of the pres-

ent invention. A talking machine of this type further includes a guide rod D upon which is slidable a carriage E carrying the reproducer F. The letter G designates the 60 lever used for starting or stopping the mechanism for rotating the cylinder. The terminal of this lever G is upturned to provide a handle portion H extending through a slot I in the top A.

65 In carrying out my invention I provide a bar 10 which is disposed below the top A beneath the guide rod D. At one end this bar is constricted or narrowed, as shown at 11, and this end portion carries a U- 70 shaped yoke 12 embracing and secured to the lever G adjacent the handle portion H thereof. The other end of the bar 10 has slidably disposed thereon a stop member 13 which is provided with an opening 14 for 75 the passage of the bar 10 and which is provided with a second opening 15 slidably upon the guide rod D and the upper end of this stop member projects into the path of travel of the carriage E.

80 In order that the stop 13 may be secured upon the bar 10 in adjusted positions, I provide a pivoted latch 16 located within a recess 17 in one side of the stop 13 and having one end projecting outwardly beyond the edge of the stop and having a 85 finger engaging head 18. The other end of this latch terminates in a tooth 19 engageable with any one of a plurality of notches 20 formed in one side of the bar 10. The 90 latch 16 is engaged by a leaf-spring 21 whereby the tooth will be urged normally into engagement with the notches.

When my device is installed it will be readily apparent that a slot 22 must be 95 provided in the top A so that the stop 13 may project therethrough.

The operation of the device is as follows:

100 The operator presses upon the button 18 to release the latch 16 from engagement with the notches 20 and this adjusts the position of the stop 13 along the bar 10 so that it will be engaged by the carriage E when the reproducer F reaches the end of the record. Additional movement of the carriage after it engages the stop will cause the bar 10 to be moved longitudinally which will result in throwing the lever G into its 105 position for stopping the mechanism rotating the cylinder. Owing to the provision of the plurality of notches 20 it will be 110

seen that the stop may be adjusted in such position as to stop the rotation of the record regardless of the length of the record.

While I have shown and described the 5 preferred embodiment of my invention, it is of course to be understood that I reserve the right to make such changes in the form, construction, and arrangement of parts as will not depart from the spirit of the invention 10 or the scope of the subjoined claims.

Having thus described my invention, I claim:

1. In combination with the control lever for the record rotating mechanism of a cylinder record type talking machine including a guide rod and a carriage slideable thereon and carrying a reproducer; an automatic stop device comprising a bar located beneath said guide rod and connected at one 20 end with said control lever, and a stop slideable upon said bar and disposable at selected positions thereon, said stop projecting in the path of travel of said carriage.
25. 2. In combination with the control lever for the record rotating mechanism of a cylinder record type talking machine including a guide rod and a carriage slideable thereon and carrying a reproducer, an auto-

matic stop device comprising a bar disposable below and in spaced parallel relation to said guide rod, said bar being connected at one end with said control lever, a stop member slidably mounted on said bar and on said guide rod and projecting into the 35 path of travel of said carriage, and means for securing said stop at adjusted positions upon said bar.

3. In combination with the control lever for the record rotating mechanism of a 40 cylinder record type talking machine including a guide rod and a carriage slideable thereon and carrying a reproducer; a stop device comprising a bar disposed below and in spaced parallel relation to said guide rod, 45 said bar being connected at one end with said control lever and having its other end formed with a plurality of notches, a stop slidably engaged upon said bar and said rod, and a spring-pressed latch member carried by said stop and engageable selectively within said notches, said stop member projecting into the path of movement of said carriage.

In testimony whereof I affix my signature.

WILLIAM C. KAUFMAN.
